UNITED STATES PATENT OFFICE.

MIKOŁAJ DUSIENCUK, OF ELLWOOD CITY, PENNSYLVANIA.

COOKSTOVE.

Application filed June 26, 1924. Serial No. 722,516.

To all whom it may concern:

Be it known that I, MIKOŁAJ DUSIENCUK, a citizen of the United States of America, residing at Ellwood City, in the county of Lawrence and State of Pennsylvania, have invented certain new and useful Improvements in Cookstoves, of which the following is a specification.

This invention relates to new and useful improvements in cook stoves, preferably of the coal range type.

An important object of the invention is to provide means for employing a coal range for heating purposes as well as for cooking.

A further object of the invention is to provide improved means for heating water which consists of an attachment carried by the fire-box end of the stove.

Other objects and advantages of the invention will be apparent during the course of the following description.

In the accompanying drawings forming a part of this specification, and in which like numerals are employed to designate like parts throughout the same,

Figure 1 is a front elevational view, partly broken away, of the cook stove embodying this invention,

Figure 2 is a side elevational view, partly broken away, of the cook stove illustrated in Fig. 1,

Figure 3 is a horizontal sectional view taken upon line III—III of Fig. 1,

Figure 4 is a vertical sectional view taken upon line IV—IV of Fig. 3,

Figure 5 is a vertical sectional view taken at right angles to Fig. 4 and upon line V—V of Fig. 2,

Figure 6 is a detail vertical sectional view taken upon line VI—VI of Fig. 3,

Figure 7 is a detail horizontal sectional view taken upon line VII—VII of Fig. 6,

Figure 8 is a detail vertical sectional view of the smoke pipe with a portion of the heat conveying pipe properly connected therewith and shows the location of one of the valves employed for controlling the direction of flow of the heat, and

Figure 9 is a detail perspective view of one type of valve used in connection with this cook stove.

In the drawings, wherein for the purpose of illustration is shown a preferred embodiment of this invention, the numeral 5 designates the front wall of the cook stove embodying

this invention. This front wall is provided with a plurality of openings which are closed by the swinging doors 6, 7, 8, 9, 10 and 11, the doors 6 and 7 being employed for closing openings leading to upper and lower oven chambers, the door 8 being employed as a coal feeding opening control, and the doors 9, 10 and 11 being employed for creating different kinds of draft for the fire-box and for causing the discharge of burned coals or ashes from the fire-box.

The top 12 of this stove is provided with a plurality of openings 13 which may be employed for cooking purposes and are provided with the removable lids 14 which are of usual construction. A heat guard 15 is carried by the rear longitudinal edge of this top 12 and is employed for carrying the hood 16 which is located above the top 12 and is provided for gathering in and feeding the heat from the cook stove through the pipe 17 which is intended to be extended upwardly through the ceiling of the room within which this stove is mounted and may be connected to a radiator not shown, located in the floor of the room arranged above the cook stove for the purpose of heating this room. This pipe 17 has a valve carrying section 17^a which is provided with laterally projecting guide grooves 18 within which the valve 19 is slidably positioned.

In Fig. 9, this valve 19 is illustrated as being formed from spring sheet metal which is bent into a tubular bead —a— and the laterally diverging plates —b—. It will be understood that the confining of the diverging plate —b— within the grooves 18 will cause the same to frictionally engage the walls of the groove for the purpose of retaining the valve in its adjusted position.

The top of the stove is further provided with a perpendicularly extending smoke pipe receiving flange 20 to which the stove pipe 21 is connected. This stove pipe extends vertically in parallelism with the heat guard 15 and projects through a suitable opening in the top of the hood 16. The upper portion 21^a of this smoke pipe is connected to the heat conveying pipe 17 by 105 the branch pipe 22 which is provided with the laterally projecting valve guiding grooves 23 within which the valve 24 is slidably positioned. This valve 24 is of the same construction as the valve 19 illustrated 110 in Fig. 9.

In Figs. 3, 6 and 7 there is shown a tubu-

lar well 25 which is open at its opposite ends for forming a communication from the top 12 to the interior of the oven 6^a which is closed by the door 6. Slidably positioned 5 within this well is an inverted cup-shaped valve 26 having a circular series of apertures 27 in its top wall, as best illustrated in Fig. 7. A stem 28 is connected to this top wall and extends upwardly through a removable 10 lid 29 which is carried by an annular flange formed in the upper end of the well 25. The outer end of this stem 26 carries a T-shaped head 30 having hooked depending arms 31 which extend through the lid 29 and constitute 15 means for limiting the relative movement between the stem 28 and the lid 29. The end wall 32 of the stove is provided with an opened bottom, three-wall extension 33 which is suitably secured to said wall 32 20 of the stove. The top of this extension 33 is closed by a removable top wall 34 which is retained in place by the bolts 35. This top wall 34 is provided with a swinging lid 36 by means of which the interior of the extension 33 may be reached. The end wall 32 of the cook stove and the opposite wall of the extension 33 are provided with a pair 25 of angular brackets 37 which are employed for supporting an opened top water vessel 30 or tank 38 having a hollow, laterally projecting boss 39 which registers with an opening 40 formed in the end wall 32 of the cook stove and which forms communication between the interior of the fire-box 41 of the 35 cook stove and the extension 33.

For the purpose of laterally moving the vessel or tank 38 for causing the boss 39 to be projected varying distances into the fire-box 41, a horizontally extending rod 42 is 40 journaled in the extension 33 and carries a pair of spaced spur gears 44 which mesh with rack bars 45 carried by the bottom wall of the vessel or tank 38. The upper edge of this tank 38 is provided with a laterally 45 extending flange 46 which acts as a stop for preventing the vessel or tank 38 from being moved such a distance that the outer end wall of the hollow boss 39 will be withdrawn from the opening 40 in the end wall 32 of 50 the cook stove. The rod 42 is provided with an operating handle 42^a, best illustrated in Figs. 1, 2 and 4, by means of which the vessel or tank 38 may be adjusted by a person standing in front of the cook stove.

55 It is now believed that the construction of this improved cook stove will be completely understood from the above detail description. The manner of operating the cook stove for utilizing the various novel features

of construction will now be described. It will be noted that the valves 19 and 24 in the heat conveying pipe 17 and the branch pipe between this pipe 17 and the smoke pipe 21^a will permit the controlling of the heat rising from the cook stove so that this heat may be discharged into a room positioned above the cook stove or the heat may be directly discharged into the smoke pipe. The heat within the oven 6^a may be directly discharged into the room within which the cook stove is located and the amount of heat discharged into the room may be regulated by operating the valve structure illustrated in Figs. 6 and 7. It will be noticed that the lid 29 may be removed varying distances from the upper end of the well 25 or the lid 29 with its inverted cup-shaped valve 26 may be entirely removed from the well for permitting the entire bore of the well to be used for discharging the heat from the oven 80 into the room.

The vessel or tank 38 is employed for heating water positioned therewith and the water may be maintained at different temperatures by adjusting the vessel or tank 85 for causing the hollow boss 39 to project different distances into the fire-box 41. The lid 36 may be opened for dipping the water out of the vessel or tank 38. When the vessel or tank 38 must be removed for cleaning 90 purposes or for repairs, the bolts 35 may be removed and the top 34 may then be taken off of the extension 33.

It is to be understood that the form of this invention herewith shown and described is to be taken as a preferred example of the same, and that various changes in the shape, size, and arrangement of parts may be resorted to without departing from the spirit 95 of the invention or the scope of the subjoined claims.

Having thus described the invention, I claim:

In a cook stove of the type described, a well formed in the stove for conducting heat 105 from the oven of the stove into the room in which the stove is located for heating said room, and a valve structure carried by said well for controlling the amount of heat conducted, said valve structure including an inverted cup-shaped element slidably in said well and having apertures in its top, a stem connected to the cup-shaped element and having a T-shaped head, and a lid for the top of said well slidably carried by the T- 110 shaped head.

In testimony whereof I affix my signature.
MIKOŁAJ DUSIENCZUK.
